(57) CLAIM

The ornamental design for a combined cosmetics dispenser and applicator, as shown and described.

DESCRIPTION

FIG. 1 is a front view showing a first embodiment of our new design for a combined cosmetics dispenser and applicator;

FIG. 2 is a rear view thereof;

FIG. 3 is a left side view thereof, the right side view being a mirror image of the side shown;

FIG. 4 is a top view thereof;

FIG. 5 is a top view thereof, with the broken line applicator surface omitted for clarity;

FIG. 6 is a bottom view thereof;

FIG. 7 is a front view showing a second embodiment of our new design;

FIG. 8 is a rear view thereof;

FIG. 9 is a left view thereof, the right view being the same;

FIG. 10 is a top view thereof;

FIG. 11 is a top view thereof with the broken line applicator surface omitted for clarity;

FIG. 12 is a bottom view thereof; and,

FIG. 13 is a front view showing the first embodiment with the applicator cap in place.

The broken lines are included for the purpose of illustrating the elements of the combined cosmetics dispenser and applicator that form no part of the claimed design.
